(57) **CLAIM**

We claim the ornamental design for a wheel hub, as shown and described.

DESCRIPTION

FIG. 1 is a front-right-side view of a wheel hub according to our new design;

FIG. 2 is a rear-left-side view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

The broken lines shown in the drawings are for the purpose of illustrating portions of the wheel hub and form no part of the claimed design.
